Primary Examiner — Sheryl Lane*Assistant Examiner* — Ieisha Price*(74) Attorney, Agent, or Firm* — Buchanan Ingersoll & Rooney PC(57) **CLAIM**

The ornamental design for an air hose hanger for a rail way vehicle, as shown and described.

DESCRIPTION

FIG. 1 is a perspective view of an air hose hanger for a rail way vehicle showing our new design;
 FIG. 2 is a right side elevational view thereof;
 FIG. 3 is a rear view thereof;
 FIG. 4 is a left side elevational view thereof;
 FIG. 5 is a front view thereof;
 FIG. 6 is a top plan view thereof;
 FIG. 7 is a bottom plan view thereof; and,
 FIG. 8 is an alternate perspective view of the air hose hanger for a rail way vehicle shown in FIG. 1.
